(57) CLAIM

The ornamental design for a body shaping garment as shown and described.

DESCRIPTION

FIG. 1 is a front perspective view of a body shaping garment showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The broken lines in the drawings depict portions of the model that form no part of the claimed design.

The portions of the body shaping garment shown in broken lines represent stitching, which does form part of the claimed design.
